UNITED STATES PATENT OFFICE.

ALCUIN E. KINTNER, OF PAINESVILLE, OHIO.

GUARD MECHANISM.

Application filed October 3, 1922. Serial No. 592,160.

This invention relates to mechanism for guarding or protecting openings in buildings, or places of possible entry, such as windows, doors and passageways, by unauthorized persons.

One object of the invention is to provide a guard mechanism of relatively simple construction.

Another object of the invention is to provide a guarding or protecting mechanism having relatively movable elements which are capable of being positioned to protect or guard an opening, or nested relatively to each other to permit unobstructed use of the opening.

Another object of the invention is to provide in mechanism of this character improved means for supporting and moving the protecting or guarding elements, whereby they may be readily moved from their operative position to their inoperative position, and vice versa.

Other objects of the invention will be apparent to those skilled in the art to which my invention relates from the following description taken in connection with the accompanying drawings, wherein

Fig. 1 is an elevation of a window frame and window and a guard mechanism embodying my invention associated therewith.

Fig. 2 is a section on the line 2—2 of Fig. 1.

Fig. 3 is an elevation showing the guard mechanism in operated position—that is, moved into position to guard the window and prevent entry therethrough, parts being broken away to facilitate the illustration.

Fig. 4 is a section on the line 4—4 of Fig. 3.

Fig. 5 is a section on the line 5—5 of Fig. 3.

Figs. 6 and 7 are fragmentary side elevational views illustrating details of construction.

In the drawings, 1 indicates a frame forming an opening 2 which is to be protected or guarded. The frame 1 constitutes the frame for a window, this being shown as the preferred application of my invention. It will however be understood that the guard mechanism, later to be described, is primarily to be intended to protect or guard an opening to prevent the entry therethrough of unauthorized persons, it being immaterial so far as the present invention is concerned and in carrying out its purpose whether the

frame forming the opening has associated with it a closing device such as a door or a window sash or sashes. The frame 1 is preferably provided with guiding devices 3, 4, 4', forming guides in different vertical planes to accommodate sliding window sashes 5, 6.

7 indicates an auxiliary frame arranged to be permanently fixed within the frame 1 in any suitable manner, preferably on the outer side of the sashes 5, 6. The auxiliary frame 7 may be incorporated with the frame 1 when assembled or applied thereto after it is completed and utilized in a building structure A. The auxiliary frame 7 serves to cover certain elements of the guard mechanism, indicated as an entirety at 8, in such manner that the latter cannot be tampered with at any time. Where the auxiliary frame 7 is applied to the frame 1 subsequent to its completion or assembly in a building structure, it is preferably constructed to support the supporting devices and guarding elements so that the latter and the auxiliary frame may be assembled as substantially a unitary structure.

The auxiliary frame 7 preferably comprises a pair of angle plates 7' and upper and lower cross members 9, 10, respectively, connected at their opposite ends to the plates 7'. Each plate 7' is arranged with one side wall 7^a flat against and secured to the inner side face of the adjacent upright 1^a of the frame 1 and its other side wall 7^b disposed in the plane of the outer edge of the uprights 1^a and extending inwardly or toward the other upright. The cross members 9, 10, cooperate with the side and end walls constituting the opening 2 to form chambers 9', 10', respectively, the purpose of which will be later set forth.

Referring to the guard mechanism 8, 11, 12, indicate a pair of devices extending along the opposite sides of the opening 2 and adapted to support a plurality of guard elements 13. By preference, the supporting devices 11, 12, extend along the vertical sides of the opening 2 and the guard elements 13 engage with the devices 11, 12, at their opposite ends and move vertically thereon. These supporting devices 11, 12 are preferably arranged relatively close to the inner faces of the side walls 7^b, this arrangement serving to position the guard elements 13 close to these walls as well as the cross members 9, 10, thereby preventing the insertion

of tools between the guard elements and the auxiliary frame 7. For this purpose, the opposite ends of each side wall 7^a of the plates 7' may be turned inwardly as shown at 7^x and such ends are formed with openings 14 which receive and form bearings for the opposite ends of the adjacent supporting devices 11 or 12. Each of the supporting devices 11, 12, comprises a rotatable shaft having (1) a threaded section 15 (extending from a point slightly above the lower edge of the upper cross member 9 to a point below the upper edge of the lower cross member 10 or a connecting plate 10^x between it and the adjacent plate 7'), which fits a screw threaded opening 13' formed in the adjacent end of each guard element 13 and co-acts therewith and in co-operation with the screw threads of the other supporting device and the threaded opening at the other end of the guard element 13 to propel the latter into and out of operative position—as will be later described—and (2) an unthreaded section 15^a (extending into the chamber 9') along which the elements 13 may slide when moved upwardly by the threaded sections 15 of the shafts 11, 12, whereby they may be nested in compact relation in their inoperative position, as shown in Fig. 1. The cross member 9 is of a width to accommodate all of the guard elements 13 when they are nested or moved into inoperative position, so as to leave the opening 2' formed by the plates 7' and cross members 9, 10, unobstructed.

Fig. 1 shows the guard elements nested together in the chamber 9'. To move the guard elements into operative position, the supporting devices 11, 12, are simultaneously rotated by a driving mechanism indicated as an entirety at 16, the screw threads on the devices 11, 12, engaging with the threads in the openings 13' of the guard elements 13 and operating therethrough to move the latter from the chamber 9' to positions bridging the opening 2', as shown in Fig. 3. The driving mechanism 16 comprises the following instrumentalities: 17 indicates bevel gears fixed to the lower ends of the shafts 11, 12. 18 indicates bevel gears fixed to a shaft 17^a and meshing with the gears 17. The shaft 17^a extends transversely of the opening 2' through the chamber 10'. The shaft 17^a is supported at one end in a standard 19; its other end extends through and is supported in an opening 20 formed in the adjacent upright 1^a, such extended end permitting the application of power to the shaft 17^a whereby the shafts 11, 12, may be rotated. 21 indicates an electric motor for driving the shaft 17^a. The motor 21 is supported upon a base 22, fixed in any desired manner to the frame member 1^b but within the side members 1^c, 1^c, as shown in Fig. 4. 22 indicates a gear train between

the motor shaft 21' and the shaft 17^a, this train preferably comprising a worm 21^a fixed to the shaft 21' and a worm gear 21^b fixed to the shaft 17^a. The direction of rotation of the motor shaft 21' to rotate the shafts 11, 12, in one direction or the other is preferably provided for by mounting the brushes for the motor on an oscillating frame 23 and moving the brushes about the axis of the armature shaft from a neutral position in either direction therefrom, this form of construction lending itself advantageously for cooperation with an automatic stop mechanism indicated as an entirety at 24, as shown in Figs. 1, 3 and 6. The brush carrying frame 23 is trunnioned on the armature shaft 21' (as will be understood from Figs. 3, 4 and 6) and one trunnion of the frame 23 has connected to it a spindle 25 which projects axially of the armature shaft 21' through an opening 1^d formed in the frame member 1^c and carries at its outer end a handle 26, whereby the brush carrying frame 23 may be moved in one direction or the other to effect operation of the motor in the desired direction. The handle 26 may be provided with a pointer 27 which will point to indicating characters (see Fig. 7) to indicate the direction in which the handle should be moved to operate the guard elements 13.

28 indicates devices extending between and connecting each guard element with the next or succeeding element. The functions of the devices 28 are to (1) co-operate with the guard elements 13 to protect the opening 2' or entry thereto by restricting the spaces between the guard elements 13 and (2) effect movement of the elements 13 from the chamber 9' into engagement with the screw threads 15 of the supporting devices 11, 12, in the manner to be later described. The connecting devices 28 preferably comprise pair of links 28^a pivotally connected at their inner ends to each other and at their remote ends to the adjoining guard elements 13, this construction permitting the guard elements to move relative to each other into a nested or compact relationship when fed upwardly by the shafts 11, 12, into the chamber 9'. I preferably provide two pairs of links 28^a between adjoining guard elements 13 and space each pair at points substantially midway between the longitudinal center line of the opening 2' and one side thereof. One link of each pair may be provided with a projecting lug 28^b to limit their unfolding movement at an obtuse angle (see Fig. 3) so that they will readily fold or articulate when the supporting devices 12^a are operated to move the guard elements 13 upwardly into the chamber 9'.

29 indicates as an entirety means arranged to engage with certain of the guard elements 13 when nested in the chamber 9'

and maintain them therein until actuated by the connecting devices 28. The maintaining means 29 are arranged at a point above the plane in which the screw threads 15 on the supporting devices 11, 12, terminate and normally project into the path of movement of the element 13 so as to engage the lower edges thereof (except the lowermost one) and prevent their engagement with the screw threads 15 until they are acted upon by the respective connecting devices 28 as each element 13 is fed downwardly one after the other. The maintaining means 29 are yieldingly supported, so that when one element 13 is propelled downwardly as already described, and it acts through its connection 28 upon the next element 13 to move it into engagement with the screw threads 15, the maintaining means 29 releases the element and then arrests the next or succeeding element 13 and holds it until it in turn is acted upon by the connecting devices 28 between it and the previously released element 13. This operation is repeated for each guard element 13 until all have been successively engaged with the screw threads 15 and moved downwardly into operative position.

The maintaining means 29 preferably comprise pairs of dogs 30, each of which may be supported at the lower end of a resilient rod 31 depending from the frame member 1^a or a plate 32 fixed thereto. As shown in Figs. 2 and 5, the dogs 30 of each pair are disposed upon opposite sides of the elements 13 and normally project below their lower edges, this arrangement permitting the dogs to ride the guard elements 13 when moved upwardly and to release them when acted upon by the connecting devices 28. To facilitate these operations, the opposing faces of the dogs 30 are beveled as shown at 33 and 34; likewise the elements 13 have beveled portions 35 in line with the dogs 30.

Of the automatic stopping means 24, 24^a indicates a rod extending longitudinally of and slidably supported on the outer surface of the upright 1^a adjacent to the motor 21, preferably by straps 24^a. Near its upper end, the rod 24^a is provided with an arm 24^b which projects through an opening 1^c formed in the adjacent upright 1^a and also an opening formed in the wall 7^a into the path of movement of the guard elements 13. Near its lower end, the rod 24^a is provided with a second arm 24^c which projects through an opening 1^d formed in the upright 1^a and an opening 7^b formed in the wall 7^a into the path of movement of the guard elements 13. When the guard elements 13 are moved from the position shown in Fig. 1 downwardly into operative position, the lowermost guard element 13 will engage the arm 24^c and move it downwardly—see Fig. 3—and it in turn will slide

the rod 24^a downwardly and the arm 24^b into position to be acted upon by the guard elements 13 when they are moved upwardly or in the opposite direction. Near its lower end, the rod 24^a is provided with a pair of spaced tappets 36, 36^a, projecting laterally, preferably in a direction opposite to the arms 24^b, 24^c, so that one or the other thereof will engage a projection 37 carried by the brush carrying frame 23. When the rod 24^a is moved in one direction or the other, as just described, it will cause the brush carrying frame 23 to move from its operated or "on" position back into neutral position, and thus stop the motor 21. In Fig. 1, the brush carrying frame 23 is shown in neutral position. If the frame 23 is oscillated clockwise, the projection 37 will be positioned in the path of movement of the tappet 36. Accordingly, when the tappet 36 is operated by the downward movement of the rod 24^a, it will move the frame 23 back into the position shown in Fig. 1. This operation will move the tappet 36^a to the position shown in Fig. 3; then if the frame 23 is oscillated to the position shown in this last mentioned view, the projection will be positioned in the path of movement of the tappet 36^a, so that when the guard elements 13 reach their limit of movement in the upward direction, they will act through the arm 24^b, rod 24^a, tappet 36 and projection 37 to move the frame from its "on" position to its neutral position, as shown in Fig. 1.

From the foregoing description it will be seen that the guard elements may be readily moved from either position to the other position, and when set in motion, they will be automatically stopped upon reaching the position towards which they are moving. It will also be seen that by providing a feed screw with which the guard elements have screw-threaded engagement, they may be propelled in either direction in a positive manner. Furthermore, this construction serves to lock the guard elements against movement along the feed screw, so that when they are moved into operative position, they are fixed or locked against movement on the feed screw. In my construction, I provide two feed screws and rotate them at the same rate of speed, thereby moving or propelling the opposite ends of the guard elements at the same speed so that they are maintained in parallel relationship. By causing each guard element to effect the engagement of the next or succeeding guard element with the screw threads 15 of the feed screws or shafts, they become uniformly spaced as they move into operative position.

In my construction I provide a sufficient number of guard elements so that when they are positioned to guard the opening 2', the

4 spaces between them will be of a size to prevent a person from entering between them. By spacing the connecting devices at points between the side edges of the opening 2, I utilize them as supplemental guard elements to restrict the spaces or openings between the guard elements 13.

5 To those skilled in the art to which my invention relates many modifications and 10 widely differing embodiments of the invention and applications thereof will suggest themselves without departing from the spirit and scope thereof. The descriptions and the disclosures herein are purely illustrative and are not intended to be in any sense limiting.

15 What I claim is:

1. In apparatus of the class described, the 20 combination with a frame work forming an opening and a chamber at one end of the opening, of a pair of shafts disposed at opposite sides of said opening, each shaft having a screw threaded section extending from end to end of the opening and an 25 unthreaded section extending into said chamber, a plurality of guard elements having screw threaded openings slidably fitting the unthreaded sections of said shafts whereby they may be nested in compact 30 relationship in said chamber or engaged with the threads of said screw threaded sections, whereby they may be propelled into operative position, and means for rotating said shafts.

35 2. In apparatus of the class described, the combination with a frame-work forming an opening and a chamber at one end of the opening, of a pair of shafts disposed at opposite sides of said opening, each shaft having a screw threaded section extending from end to end of the opening and an unthreaded section extending into said chamber, a plurality of guard elements having screw threaded openings slidably fitting the unthreaded sections of said shafts whereby they may be nested in compact 40 relationship in said chamber or engaged with the threads of said screw threaded sections, whereby they may be propelled into operative position, means for rotating said shafts, and means for stopping the rotation of the shaft when said guard elements reach a predetermined position in their movement in one direction.

45 3. In apparatus of the class described, the combination with a frame work forming an opening and a chamber at one end of the opening, of a pair of shafts disposed at opposite sides of said opening, each shaft having a screwthreaded section extending from end to end of the opening and an unthreaded section extending into said chamber, a plurality of guard elements having screw threaded openings slidably fitting the 50

unthreaded sections of said shafts whereby they may be nested in compact relationship in said chamber or engaged with the threads of said screw threaded sections, whereby they may be propelled into operative position, means for rotating said shafts, and means for stopping the rotation of the shafts when said guard elements reach a predetermined position in their movement in either direction.

5. In apparatus of the class described, the combination with a frame work forming an opening and a chamber at one end of the opening, of a pair of shafts disposed at opposite sides of said opening, each shaft having a screw threaded section extending from end to end of the opening and an unthreaded section extending into said chamber, a plurality of guard elements having screw threaded openings slidably fitting the unthreaded sections of said shafts whereby they may be nested in compact relationship in said chamber or engaged with the threads of said screw threaded sections, whereby they may be propelled into operative position, means for rotating said shafts, and means for feeding said guard elements successively into engagement with the screw threads of said screw threaded sections.

5. In apparatus of the class described, the combination with a frame work forming an opening and a chamber at one end of the opening, of a pair of shafts disposed at opposite sides of said opening, each shaft having a screw threaded section extending from end to end of the opening and an unthreaded section extending into said chamber, a plurality of guard elements having screw threaded openings slidably fitting the unthreaded sections of said shafts whereby they may be nested in compact relationship in said chamber or engaged with the threads of said screw threaded sections, whereby they may be propelled into operative position, means for rotating said shafts, and means for feeding said guard elements successively into engagement with the screw threads of said screw threaded sections, said last mentioned means comprising devices for releasably holding said elements in said chamber and connections between said elements operating to effect their release from said devices successively.

6. In apparatus of the class described, the combination of a frame work forming an opening to be guarded, a pair of shafts disposed along opposite sides of said opening, each shaft having a screw threaded section extending from end to end of the opening and an unthreaded section extending beyond one end thereof, a plurality of guard elements having screw threaded openings slideable on the unthreaded sections of said shafts and arranged to engage the threaded sections thereof, means for rotating said shafts

- whereby said elements are propelled or moved across said opening to form a guard therefor, devices for releasably holding said elements in nested relationship along the unthreaded sections of said shafts, and connections between said elements operating to effect disengagement thereof from said holding means one after another as they are fed across said opening.

7. In apparatus of the class described, the combination of a frame work forming an opening to be guarded, a pair of shafts disposed along opposite sides of said opening, each shaft having a screw threaded section extending from end to end of the opening and an unthreaded section extending beyond one end thereof, a plurality of guard elements having screw threaded openings slideable on the unthreaded sections of said shafts and arranged to engage the threaded sections thereof, means for rotating said shafts whereby said elements are propelled or moved across said opening to form a guard therefor, a pair of yieldable devices for releasably holding said elements in nested relationship along the unthreaded sections of said shafts, and connections between said elements operating to effect disengagement thereof from said holding means one after another as they are fed across said opening.

8. In apparatus of the class described, the combination of a frame work forming an opening to be guarded, a pair of shafts disposed along opposite sides of said opening, each shaft having a screw threaded section extending from end to end of the opening and an unthreaded section extending beyond one end thereof, a plurality of guard elements having screw threaded openings slideable on the unthreaded sections of said shafts and arranged to engage the threaded sections thereof, means for rotating said shafts whereby said elements are propelled or moved across said opening to form a guard therefor, devices for releasably holding said elements in nested relationship along the unthreaded sections of said shafts, and foldable links between said elements operating to effect disengagement thereof from said holding means one after another as they are fed across said opening.

9. In apparatus of the class described, the combination with a frame-work forming an opening and a chamber at one end thereof, of a pair of feed screws disposed at opposite sides of said opening and extending from end to end thereof, a plurality of guard elements having screw threaded engagement at their opposite ends with said feed screws, means for rotating said feed screws to move said guard elements into operative relation to said opening to guard it or into said chamber, connections between said guard elements, and means in said chamber co-acting with said connections to control the delivery of said elements to the threads of said feed screws, whereby said elements are uniformly spaced along said feed screws when moved into guarding position.

10. In apparatus of the class described, the combination with a frame-work forming an opening, of an auxiliary frame fitting said opening and co-operating with said frame-work to form a chamber at one end thereof, a pair of feed screws disposed at opposite sides of said opening and extending from end to end thereof, a plurality of guard elements having screw threaded engagement at their opposite ends with said feed screws, means for rotating said feed screws to move said guard elements into operative relation to said opening to guard it or into said chamber, connections between said guard elements, and means in said chamber co-acting with said connections to control the delivery of said elements to the threads of said feed screws, whereby said elements are uniformly spaced along said feed screws when moved into guarding position.

11. In apparatus of the class described, the combination with a frame-work forming an opening, of a cross member at one end of said opening and co-operating with said frame-work to form a chamber, a pair of feed screws disposed at opposite sides of said opening and extending from end to end thereof, a plurality of guard elements having screw threaded engagement at their opposite ends with said feed screws, means for rotating said feed screws to move said guard elements into operative relation to said opening to guard it or into said chamber, connections between said guard elements, and means in said chamber co-acting with said connections to control the delivery of said elements to the threads of said feed screws, whereby said elements are uniformly spaced along said feed screws when moved into guarding position.

12. In apparatus of the class described, the combination with a frame-work forming an opening to be guarded, and a chamber at one end thereof, of a pair of feed screws disposed at opposite sides of said opening and extending from end to end thereof, a plurality of guard elements having screw threaded engagement at their opposite ends with said feed screws, means for rotating said feed screws to move said elements into operative relation to said opening to guard it or into said chamber, and spaced connections between said elements serving to restrict the spaces between them.

13. In apparatus of the class described, the combination with a frame-work forming an opening to be guarded, and a chamber at one end thereof, of a pair of feed screws disposed at opposite sides of said opening and extending from end to end thereof, a plurality of guard elements having screw threaded engagement at their opposite ends with said feed screws, means for rotating said feed screws to move said guard elements into operative relation to said opening to guard it or into said chamber, connections between said guard elements, and means in said chamber co-acting with said connections to control the delivery of said elements to the threads of said feed screws, whereby said elements are uniformly spaced along said feed screws when moved into guarding position.

threaded engagement at their opposite ends with said feed screws, means for rotating said feed screws to move said elements into operative relation to said opening to guard it or into said chamber, and means for controlling the delivery of said elements from said chamber into engagement with the threads of said feed screws when being moved into position to guard said opening.

14. In apparatus of the class described, the combination with a frame-work forming an opening to be guarded, and a chamber at one end thereof, of a pair of feed screws disposed at opposite sides of said opening and extending from end to end thereof, a plurality of guard elements having screw threaded engagement at their opposite ends with said feed screws, means for rotating said feed screws to move said elements into operative relation to said opening to guard it or into said chamber, means for controlling the delivery of said elements from said chamber into engagement with the threads of said feed screws when being moved into position to guard said opening, and means for stopping said rotating means when said guard elements reach a predetermined position during movement in either direction.

15. In apparatus of the class described, the combination with a frame work forming an opening to be guarded, of a pair of supporting devices arranged along two sides of the opening, guard elements supported at their opposite ends on said devices and ar-

ranged to be disposed in nested relation at one side of the opening, means operating to successively engage said elements in their nested position and move each relative to the adjacent element into spaced relation thereto and to move all of the elements so engaged and spaced along said devices to arrange them in operative relation to the opening, said means comprising screw threads on said supporting devices fitting threaded openings formed in the opposite ends of said elements, and means serving to space said elements relative to each other as they are moved from a nested relationship into spaced relationship.

16. In apparatus of the class described, the combination with a frame work forming an opening to be guarded, of a plurality of guard elements disposed transversely of said opening and arranged to be nested at one side thereof, means for supporting the opposite ends of said devices in nested relation and for moving them successively from their nested relation relative to the opening, and means co-operating with the moving elements of the last mentioned means for effecting and controlling the successive movement of said guard elements to uniformly space the latter when engaged by the moving elements of said supporting and moving means.

In testimony whereof, I have hereunto affixed my signature.

ALCUIN E. KINTNER.
